UNITED STATES PATENT OFFICE.

CHARLES H. ALBERT, OF RACINE, WISCONSIN, ASSIGNOR, BY DIRECT AND MESNE ASSIGNMENTS, TO THE HARTMANN TRUNK COMPANY, OF RACINE, WISCONSIN, A CORPORATION OF WISCONSIN.

GANG-PUNCH.

1,164,158.

Specification of Letters Patent. Patented Dec. 14, 1913.

Application filed April 19, 1912. Serial No. 691,803.

To all whom it may concern:

Be it known that I, CHARLES H. ALBERT, a citizen of the United States, and resident of Racine, in the county of Racine and State 5 of Wisconsin, have invented new and useful Improvements in Gang-Punches, of which the following is a description, reference being had to the accompanying drawings, which are a part of this specification.

10 This invention relates to improvements in gang punches which are particularly adapted for perforating long strips of material with a plurality of apertures.

15 In the manufacture of trunks of the higher grade the corner edges and other portions of the trunks are reinforced with strips of fiber or other material. The strips are provided with lines of closely positioned perforations along their side edges to properly space 20 and accommodate tacks used in fastening the strips to the trunks.

25 It is one of the objects of this invention to provide a gang punch with a plurality of punches and dies of which any number may be used to perforate the fiber or other material, as desired, without removing the inactive punches from the machine.

30 A further object of the invention is to provide a gang punch having a plurality of punches with a series of back members which are adapted to engage the punches desired to be utilized at the particular time.

35 A further object of the invention is to provide a gang punch of a given size which is adapted to perforate strips of material of any length desired.

40 A further object of the invention is to provide a gang punch of the character described with a guard so arranged and positioned that it is impossible for the fingers of the operator to get beneath the movable head of the machine.

45 A further object of the invention is to provide a gang punch of the character described with means for removably holding the dies in their holder to prevent elongation of the holder which ordinarily takes place when a number of dies are driven fitted to their holder.

50 A further object of the invention is to provide a gang punch of the character described with a plurality of loosely held punches, any number of which may be easily engaged to perforate material without removing the inactive punches from the machine.

With the above and other objects in view, the invention consists of the improved gang punch and its parts and combinations, as set forth in the claims, and all equivalents thereof.

63 In the accompanying drawings in which the same reference characters indicate the same parts in all of the views: Figure 1 is a longitudinal sectional view of the improved gang punch taken on line 1—1 of 65 Fig. 2; Fig. 2 is a transverse sectional view thereof taken on line 2—2 of Fig. 1; Fig. 3 is a sectional detail view on a larger scale of a portion of the punch taken on line 3—3 of Fig. 4; Fig. 4 is a transverse sec- 70 75 Fig. 5 is a side view, on a still larger scale, of one of the punches; Fig. 6 is a vertical sectional view of one of the dies; Fig. 7 is a top view of one of the back members; and Fig. 8 is a top view of another back member.

Referring to the drawings the numeral 10 indicates the legs and ends of the main frame of the improved gang punch and 11 80 the table or bed thereof, connecting the ends together, and which is provided in its upper portion with a longitudinally extending die-plate slot or groove 12 to accommodate a die plate 13 positioned therein and fastened to 85 the bed by bolts 14. The legs of the frame are connected together and braced by stay rods 10'. The end portions of the main frame are provided with outwardly projecting bearings 15 having vertically extending 90 openings therein through which reciprocate connecting rods 16. Two of these connecting rods are positioned at each end of the machine and their upper end portions are reduced in diameter and these reduced portions extend through openings provided in the movable head 17 and have nuts threaded thereon to firmly connect the parts together. The shoulders 18, formed by the reduced 95 portions of the rods, bear against the lower 100 parts of the movable head. The rods positioned at each end of the machine are spaced a considerable distance apart and at their lower end portions extend on opposite sides of the eccentric end portions 19 of a shaft 20 journaled in the end portions of the main frame. The lower end portions of the rods are also reduced in diameter and extend through connecting blocks 21 and are provided with nuts on their ends for firmly 105 110

securing the blocks to the rods. These blocks are provided with rectangular openings 22, in which play reciprocal journal blocks 23. The eccentric end portions 19 of the shaft 20 extend into and have their bearings in these blocks and serve to reciprocate the blocks and connected parts vertically.

A belt pulley 24, journaled on the shaft, is 10 adapted to be clutched thereto when desired to reciprocate the punch head 17 by means of a clutch mechanism 25 of ordinary construction. The clutch is operated by means of the foot treadle 26 in the ordinary manner. The die plate 13, positioned within the die plate groove 12, is provided with a line of shouldered openings 27 into which the annular dies 28 are inserted and rest upon the shoulders 29 of said openings. The upper portions of the dies are reduced in diameter to form annular shoulders 30 which are approximately flush with the upper surface of the die holder when the said dies are inserted therein.

25 A locking plate 31, fastened to the top of the die plate by screws 32 (only one being shown), is provided with a line of openings 33 through which the reduced portions of the dies extend with the plate engaging the shoulders of the dies to firmly lock the dies in the holder.

The bed plate 11 of the punch is provided with a line of slots 34 which register with the openings of the die holder to permit the 35 punch or waste parts to be discharged from the openings 35 of the dies.

An angular guard 36 is also fastened to the die holder 13 and is spaced a sufficient distance above the holder to permit the insertion of the material to be punched therebetween by a spacing bar 37. The upstanding flange 38 of the angular guard is positioned just in front of the path of travel of a punch holder 39 carried by the head 17, 40 and the upper edge of the flange is on a plane slightly above the plane of the lower surface of the punch holder when the punch holder is in its upper position, and thus serves to prevent the fingers of the operator 45 from getting beneath the punch holder.

The horizontal portion of the angular guard also serves as a stripper plate for the punches 40 and is provided with openings 41 which register with the openings of the dies and through which the punches 40 pass in entering the dies.

The movable head 17 of the punch is formed with a recessed portion 42 forming a shoulder 43. The punch holder 39 is positioned within this recess and is fastened to the movable head by a number of bolts 44 which extend through the head and are tapped into the punch holder. The upper surface of the punch holder is spaced from the shoulder 43 of the head to accommodate

one of a plurality of abutting plates 44 which are adapted to hold the punches desired to be used in active position.

The punch holders are provided with shouldered openings 45 which register with the dies 28, and the shouldered punches 40 are formed to snugly fit into these openings, and the upper ends of the punches are flush with the upper surface of the punch holder. The lower portions of the punch shanks are 75 reduced in diameter to form shoulders 46 which are adapted to rest on the shoulders of the shouldered openings of the punch holder to prevent the withdrawal of the said punches downwardly from the holder. 80

The abutting plates 44 have depending end flanges 47 which extend over the ends of the punch holder to prevent endwise movement of the abutting plates, and depending blocks 48, bolted to the movable head, are 85 adapted to firmly clamp the particular abutting plate in use to the movable head.

The abutting plate shown in Figs. 3 and 7 is provided with a number of transverse rearwardly extending slots 49 which register 90 with alternate punches to permit said registering punches to be pushed upwardly when engaging the work and thus render said alternate punches inactive with reference to punching holes through the strip of material 95 placed beneath the angular guard. The alternate punches not in register with the slots will abut against the solid portions of the plate and the punches will be forced through the material by the movement of the punch head. The abutting plate shown in Fig. 8 is adapted to engage all of the punches and render each one active in punching material. It is thus obvious that by providing abutting plates with slots or openings positioned 100 at different distances apart that any combination of active punches may be obtained by merely substituting one plate for another. 105

The connecting rods at each end of the gang punch are spaced a sufficient distance apart to permit strips of material of a length greater than the machine to be fed endwise to the machine and punched in sections until the entire length of the strip is perforated. 110

From the foregoing description it will be seen that the gang punch is adapted to punch holes in strips of material at different distances apart and may be easily changed to vary the distances as desired. It will also be seen that the punches and dies are firmly held in position and may be easily replaced when worn or broken. 115

What I claim as my invention is:

1. A gang punch, comprising a die holder 125 provided with a plurality of dies, a punch holder provided with a plurality of shouldered openings extending therethrough, shouldered punches positioned within the openings and movable endwise therein and adapted to coöperate with the dies, and an 130

- abutting plate extending over the ends of the punches and provided with cutaway portions registering with some of the punches to permit said registering punches to move 5 endwise in the punch holder when engaged by the material to be punched.
2. A gang punch, comprising a die holder provided with a plurality of shouldered die openings, shouldered dies extending into the 10 openings, a perforated plate fastened to the die holder and through which the dies extend and with their shoulders bearing against the plate, a punch holder provided with a plurality of shouldered openings extending therethrough, shouldered punches positioned within the punch holder openings and movable endwise therein and adapted to coöperate with the dies, and an abutting plate extending over the ends of the 15 punches and provided with cutaway portions registering with some of the punches to permit said registering punches to move endwise in the punch holder when engaged by the material being punched.
- 20 3. A gang punch, comprising a die holder provided with a plurality of shouldered die openings, shouldered dies extending into the openings, a perforated plate fastened to the die holder and through which the dies extend and with their shoulders bearing 25 against the plate, a punch holder provided with a plurality of shouldered openings extending therethrough, an angled guard member positioned between the two holders 30 and spaced above and fastened to the die holder and having a portion extending in front of and above the lower surface of the punch holder, shouldered punches positioned within the punch holder openings 35 and movable endwise therein and adapted to 40
- coöperate with the dies, and an abutting plate extending over the ends of the punches and provided with cutaway portions registering with some of the punches to permit said registering punches to move endwise in 45 the punch holder when engaged by the material being punched.
4. A gang punch, comprising a frame provided with a bed portion adapted to hold a line of dies, a movable head positioned 50 above the bed portion and provided with means for holding a line of punches registering with the dies, reciprocating blocks positioned at opposite ends of the frame, and spaced reciprocating means connecting 55 the movable head to the blocks, said means being out of alinement with the lines of punches and dies to permit the endwise feed of material between the punches and dies.
5. A gang punch, comprising a frame provided with a bed portion adapted to hold a line of dies, a movable head positioned 60 above the bed portion and provided with means for holding a line of punches registering with the dies, reciprocating blocks 65 positioned at opposite ends of the frame, and a pair of spaced reciprocating rods positioned at each end of the frame and connecting the movable head to the blocks, said rods being spaced in a plane on opposite 70 sides of the lines of punches and dies to permit endwise feed of material therebetween and between the punches and dies.

In testimony whereof, I affix my signature, in presence of two witnesses.

CHARLES H. ALBERT.
